TYPEWRITER CARRIAGE RETURN AND
PLATEN SPACER MECHANISM

Enrique Perozo, Habana, Cuba

Application September 3, 1935, Serial No. 39,007

1 Claim. (Cl. 197—65)

The invention relates to a typewriter attachment and more especially to a combination typewriter carriage return and platen spacer.

The primary object of the invention is the provision of an attachment of this character, wherein through the use thereof a typewriter carriage will be automatically returned to starting position and simultaneously therewith the platen will be actuated for line spacing purposes, thereby eliminating these burdens upon the user of the machine, the return of the carriage being effected by manipulation of a key located outside of the keyboard while rotation of the platen for line spacing is automatically had when the carriage is shifted for the return thereof to starting position.

Another object of the invention is the provision of an attachment of this character, wherein in the construction thereof is such as to permit the use in various makes of typewriters and thus avoiding hand shifting in line spacing as is customary in the operation of the typewriter.

A further object of the invention is the provision of an attachment of this character, which is extremely simple in its construction, thoroughly reliable and efficient in its operation, readily and easily mounted upon a typewriter without requiring any material alterations in the construction thereof, strong, durable, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a diagrammatic side elevation of a typewriter, it being represented by dotted lines and having the attachment constructed in accordance with the invention applied thereto, the attachment being in full lines.

Figure 2 is a rear elevation of the rack and gearing adjuncts of the attachment.

Figure 3 is a vertical transverse sectional view through one of the gears of the train employed in the attachment.

Figure 4 is a top plan view of the platen spacer trigger.

Similar reference characters indicate corresponding parts throughout the several views in the drawings.

Referring to the drawings in detail, A designates generally the main frame of a typewriter,

and B the traveling carriage of said typewriter. This carriage supports the roll platen C which is journaled in the usual manner and is hand turned for line spacing in the operation of the typewriter. The platen is automatically rotated for 5 line spacing and the carriage returned to starting position in the use of the attachment constituting the present invention and hereinafter fully described.

The carriage return is had through the use of a key 10 having a stem 11 which is mounted transversely in the frame A for sliding movement and this key is located above the keyboard of the typewriter to protrude forwardly of the front of the frame A of the latter. At one side of the 15 frame A, or in other words, secured to one end of the said frame A is a bracket 12 having an upstanding post 13 and a horizontal base 14, respectively. The post 13 at its upper end provides a guide 15 for a toothed rack 16 detachably joined with the stem 11 of the key 10 so that the rack will be held in meshing engagement with a rack pinion 17 fixed to a rotatable shaft 18. This shaft 18 is journaled in the post 13 and a support 19 fixed to the base 14 of the bracket 12 to be disposed at right angles to the stem 11 and cross-wise thereof. The shaft 18 carries a worm screw 20 meshing with a worm pinion 21 upon a hub 22 of a driving gear 23, it being journaled upon a stud axle 24 carried by a support 25 joined with 30 the base 14 of the bracket 12. The gear 23 is one of a train of meshing gears and pinions 26, these being journaled on the support 25. The outermost gear 26 of the train meshes with a rack bar 27 fixed to the carriage B at the rear thereof and longitudinally disposed therein. Thus it will be seen that when the rack 16 is operated on pressing the key 10 the train of gearing will be set in motion and this motion will be transmitted to the rack bar 27 so that the carriage B will be 40 driven to return position or initial starting position, the carriage being advanced as usual under spring tension and escapement control on operating the keys of the keyboard (not shown) of the typewriter.

Surrounding the stem 11 of the key 10 within the frame A of the typewriter is a coiled compression spring 28, it having connection with a collar 29 on the stem 11, the collar being fixed thereto and with a collar 30 made fast to the frame A and loosely surrounding the stem 11 of the key 10. This spring 28 is a compensator for the rack 16 meshing with the pinion 17 when the carriage B is advanced as usual by operating the keys of the keyboard of the typewriter. 55

In other words, when it is desired to return the carriage to starting point or position after it has been advanced from right to left under the operation of the keys of the keyboard of the typewriter, the key 10 is depressed causing the rack 16 to operate the pinion 17 thus under full movement of the rack the carriage is returned to starting position. The full rearward movement of the rack for the return of the carriage 10 presses the spring 28 and as the typewriter is advanced in a letter spacing direction by manipulation of the keys of the keyboard of the typewriter through the conventional escapement mechanism D the rack 16 will be moved forwardly in a step by step action under the tension of the spring 28 so that the key 10 will be reset on completion of the advancement of the carriage from right to left and thus by depressing the key 10 the carriage can be returned to normal starting position from the right hand side of the machine.

The platen C in the carriage B is rotated through ratchet mechanism (not shown), this usually being manually operated and included 25 with the attachment is an actuator trigger 31 for said ratchet mechanism and such trigger is extended forwardly of the carriage from the pivotal point 32 of the same therewith to protrude into the path of a tripping roller or abutment 33 30 upon the frame A at the left hand side thereof so that when the carriage is returned to the right hand end of the frame the platen C will be automatically rotated for line spacing of the typed matter in the operation of the typewriter. The trigger 31 has pivoted thereto a one-way acting trip tip 34 which overrides the roller or abutment 33 when the carriage is moving from right to left so as not to disturb the trigger 31 under this movement yet when said carriage is moved from left to right for the return thereof to

starting position the tip 34 is latched so as to have the trigger 31 operated for line spacing of the platen under this return movement of the carriage. The trip tip 34 is pivoted at 35 to the trigger 31 and a spring 36 connected with the said trigger and tip normally holds the tip in latching position with the trigger.

The ratchet mechanism (not shown) for line spacing is manually set as is customary to regulate the extent of line spacing required of the platen and this trigger 31 automatically effects the turning of the platen for the desired line spacing in the writing when the typewriter is being operated while the carriage is returned to starting position on actuating the key 10 manually.

What is claimed is:

An attachment for a typewriter having a movable carriage and an escapement mechanism for controlling the movement of the carriage in letter spacing direction, comprising a substantially Y-shaped bracket for mounting on a typewriter frame for vertical disposition thereof, a key stem slidably fitted in the frame of said typewriter, a bearing on the bracket for the said key stem, said key stem having a reduced inner end slidably fitting said bearing, a rack on said stem next to the reduced end, a train of gearing supported from said bracket, a worm gear fitting one of the gears of the train, a worm shaft bridging the worm gear and meshing therewith, a rack pinion on said worm shaft and meshing with the rack on said stem, a rack on the movable carriage of the typewriter and engaged by another gear of said train, a key head on said stem and located spaced from the front of the said typewriter frame and a spring fitting the frame and the said stem for tensioning the latter.
